UNITED STATES PATENT OFFICE.

ALBERT B. DICK, OF LAKE FOREST, ILLINOIS, ASSIGNOR TO A. B. DICK COMPANY,
OF CHICAGO, ILLINOIS, A CORPORATION OF ILLINOIS.

SHEET-FEEDING APPARATUS.

No. 873,848.

Specification of Letters Patent.

Patented Dec. 17, 1907.

Application filed May 28, 1907. Serial No. 376,125.

To all whom it may concern:

Be it known that I, ALBERT B. DICK, a citizen of the United States, residing at Lake Forest, in the county of Lake and State of

5 Illinois, have invented a certain new and useful Improvement in Sheet-Feeding Apparatus, of which the following is a specification.

This invention is designed particularly for use in connection with printing machines 10 and the like, and has for its object the provision of a simple and durable mechanism for successively feeding sheets of paper or similar material to such a machine reliably and at substantial speed.

15 Although not limited thereto, the invention is especially adapted for use in connection with stencil-printing machines of the rotary type, in which is employed a drum, upon the surface whereof is placed a waxed 20 stencil-sheet having openings therein corresponding to type characters. A printing machine of this type is illustrated in Letters Patent No. 749,984, granted to me January 19, 1904. In machines of this type heretofore commonly employed, it has been customary to feed the sheets of impression paper under the rotary drum and against a suitable paper-stop. Due to the rotation 25 of the drum, such sheet is, when being im- 30 printed upon, gripped between the periphery of the drum and that of an underlying pressure-roller and fed from the machine as the sheet is imprinted upon through the stencil. Among the objections due to this 35 method of operation, is that the impression sheet is commonly at rest until its feeding movement is commenced by reason of the impingement of the stencil-sheet thereon. Due to this, not only is an objectionable 40 strain thrown upon the delicate stencil- sheet, but in addition the first line or lines of the stencil are apt to be blurred. Moreover, in certain of the machines of the type referred to, it is a matter of some difficulty 45 to determine at what point upon the im- 50 pression sheet the imprinting from the stencil is to be commenced. Again, due to the necessity for accurately locating the forward edge of the impression sheet be- 55 neath the drum, so that the same may be brought into proper coaction with the periphery of such drum and that of the under- 60 lying pressure-roller, the operation of feed-

ing the sheets is necessarily time-consuming, permitting the production of newer prints 55 within a given time than are now considered desirable.

In the preferred form in which the present invention has been embodied, I employ a stencil - duplicating machine of the type 60 above referred to, including the rotary drum and the underlying pressure-roller adapted to coact therewith in the production of stencil - printed copies. In conjunction with such drum and roller, I provide an initial- 65 feed device actuated by a moving part of the apparatus, such, for example, as the stencil-carrying drum or one of the gears by means whereof such drum is operated. This feed de- 70 vice is of the intermittent variety and the actuating mechanism therefor is of such character as that the moment at which said device is set in operation may be nicely determined with reference to the movement of the stencil-printing drum and therefore of the sten- 75 cil-sheet carried by such drum. Moreover, such device is of such character as to feed the impression sheet forward at practically the same speed as the surface speed of the stencil-carrying drum; in other words, the surface 80 speed of the impression sheet and that of the stencil-sheet are substantially the same. Said device comprises essentially a pair of feed-rolls and means controlled by a moving part of the duplicator, such as the stencil-carrying 85 drum, as above indicated, for intermittently operating said rolls so as to feed the impres- 90 sion sheets successively forward to a point where the same may be gripped between the periphery of the stencil-carrying drum and that of the pressure-roller and thence fed from the machine and simultaneously im- 95 printed upon. At the moment that the por- 100 tion of the stencil upon which has been cut the first line of the matter to be duplicated comes into contact with the impression sheet, both the stencil-sheet and the impres- 105 sion sheet are traveling at the same speed, thereby removing the possibility of blurring, which has heretofore proved objectionable as above stated. Again, since the means for advancing the impression sheet, to wit, the feed-rolls, are governed as to their effective operation by means of a connection with a moving part of the apparatus, such as the stencil-carrying drum, and since such con-

nection is capable of ready adjustment by the operator, the point upon the impression sheet where it is desired to commence the printed characters may be readily determined and thenceforth be substantially independent of the operator and the precise moment at which the sheets are presented to the feed device. Due, also, to such means for adjustment, the point at which the matter cut in the stencil is to be reproduced upon the stencil-sheet may readily be determined and provided for, quite regardless of the position upon the stencil-sheet of the type characters formed therein.

15 Such a preferred embodiment of the invention as that above referred to is indicated in the drawings, in which

Figure 1 is an elevation, partly in section on the line 1—1, Fig. 2, illustrating the invention in connection with a stencil-duplicator; Fig. 2 is a sectional plan on the line 2—2 of Fig. 1 and looking in the direction of the arrow adjacent to said line; and Fig. 3 is a section on the line 3 of Fig. 1, looking in the direction of the arrow adjacent to said line.

Referring to these drawings, A indicates the base of the machine, upon which is supported a suitable frame comprising, usually, side members B, between which is pivoted, 20 upon stub-shafts c, the stencil-carrying drum C upon the periphery whereof the stencil-sheet is stretched. Directly underlying the stencil-carrying drum and operated by peripheral contact with the drum or the intervening impression-sheet, is the pressure-roller D, here shown as journaled, at d, upon arms E hinged at e to the side members of the frame. A spring F tends to exert upward pressure upon said pressure-roller. 25 Cams f, mounted upon a shaft f', actuated by a hand-piece outside the frame of the machine, operate, when said hand-piece is moved to one or the other of its two positions, to move the pressure-roller D to operative or inoperative position, the former of which positions is illustrated in Fig. 1. The mechanism as thus far described forms no part of the present invention.

Turning now to the sheet-feeding apparatus, G, H; designate sheet-feeding rolls, one above the other, each mounted upon a shaft g, h, the ends whereof are mounted in supports I, I', on either side of the machine and adjacent to the side members B of the frame thereof. The roll G is here shown as formed in sections G', G'', such sections being mounted upon a sleeve g' carried by said shaft g. Said sleeve is loosely mounted upon said shaft and is provided at one end with the pinion g², which engages with a corresponding pinion h' upon the end of the roll H. That end of the sleeve g' opposite the end at which said pinion g² is arranged, is provided with a clutch-member g³ coacting with a 50 similar clutch-member g⁴, which, with the

pinion g⁵ secured thereto, are keyed or pinned to the shaft g. A spring g⁶ tends to force the sleeve g' toward the left (Fig. 2), and therefore to maintain the parts g³, g⁴ in contact. The pinion g⁵ meshes with a corresponding pinion L carried by a stub-shaft secured to the support I. Said stub-shaft also carries, adjacent to said pinion L, a friction-sheave l, this being immovable relatively to said pinion L. It is apparent that movement transmitted to the friction-sheave l will, through the pinions L and g⁵, transmit corresponding movement to the shaft g, and thence through pinions g², h' to the shaft h, to which the lower feed-roll H is secured.

For the purpose of the present disclosure, and as indicating merely a preferred form, I have here shown the feed-roll-actuating device as carried by the drum C. It comprises a sector M pivoted upon one of the stub-shafts c and having a serrated edge m adapted to coact with the surface of the friction-sheave l, said friction-sheave having preferably a periphery of yielding material, such as rubber, felt, or leather. Said sector is also provided with an elongated slot m' through which extends a screw m², the end of which is received in a suitably threaded orifice in the adjacent head of the drum.

In Fig. 1, the drum is shown as provided with two stencil-securing devices, one, N, (in dotted lines) for the forward edge of the stencil, and another, N', for the rear edge of the stencil. It is apparent that there will be no coaction between the stencil-carrying drum and the sheet-feeding device save at such time during the movement of said drum as the serrated edge of the sector M is brought into contact with the periphery of the roll l, and since such sector is adjustable on said drum, the moment of coaction may readily be predetermined and provided for (by moving the sector relatively to the drum and then clamping it), so as to determine, with reference to the moment when the first line of the stencil will reach printing position (over the center of the pressure-roller), the moment at which the rolls G and H will be set in operation to feed the forward edge of the impression sheet forward and into the grip of the pressure-roller and drum. The adjustment of the sector, therefore, will determine at what point upon the impression sheet the stencil characters are to be produced. It will also be apparent that, due to the construction described and since the impression sheet is advanced by the feeding device at the same rate of speed as that at which the stencil-sheet travels, not only does the impression sheet impose no drag upon the stencil-sheet in order to continue the movement of the former through the machine, but also, as incident of this, there is no relative movement of the stencil-sheet and impression sheet and therefore no tendency 130

toward blurring the imprint, as heretofore, where the movement of the impression sheet through the machine, and particularly the commencement of such movement, has been 5 due in part to the pull of the stencil-covered periphery of the drum upon the upper surface of the impression-sheet.

P designates a feed-table, upon which the sheet-pile p may be laid, said table being provided, as usual, with adjustable guides p' for 10 positioning such pile. In the present instance, the feed-table is shown as pivoted to the frame at p². Between such feed-table and the stencil-drum, I prefer to employ a 15 plate Q secured at its ends to the frame of the machine and provided with a longitudinal slot q directly over the roll H, said roll operating within such slot, its periphery being on a line with or slightly above the upper surface 20 of said plate. I also prefer to employ in connection with said plate a sheet-guide R, here shown as secured to the supports I, I', and arranged obliquely to form a wedge-shaped opening into which the sheets may be 25 passed to the rolls G, H. Said guide-plate R is here shown as provided with fingers r co-extensive in size with the sections G' of the upper feed-roll G and terminating immediately below and slightly rearward of said sections. 30

The operation of the apparatus has heretofore been explained. It remains only to add that while in the preferred form in which the invention may be embodied the feeding device is so arranged as to forward the impression-sheets at the same speed as that at which the stencil on the rotary drum moves, yet if for any reason the stencil should be found to travel faster than the rate at which 35 the impression-sheet is fed, the coaction of the drum and the underlying pressure-roller will pass the sheet through the machine without drag upon such sheet by the feed-rolls G, H, this being due to the ratchet or clutch g³, g⁴, heretofore described, which permits the roll G (and therefore the roll H in mesh therewith) to be operated not only by the sector M and sheave l but also by the pull of the impression-sheet. 45

In the preferred apparatus here described, the sector M is mounted upon the drum rather than upon another moving part of the apparatus, such, for example, as one of the gears by means of which the drum may be 50 operated, for the purpose of making the machine more compact and conducing to the ease with which said sector may be adjusted for the purpose hereinbefore referred to. It will also be understood, as above indicated, 55 that it is not designed to limit the use of the feed apparatus herein described to a stencil-duplicating machine, as the same may be employed to advantage in machines of another and different type, particularly such as 60 employ a type-form and platen (the latter 65

either rotary or reciprocating) for effecting the imprints upon the impression-sheets.

Having now described my invention, what I claim as new therein and desire to secure by Letters Patent is as follows:—

1. The combination with a printing-drum and an underlying pressure-roller, of two feed-rolls in vertical alinement and in juxtaposition to the point of coaction of said drum and roller, said rolls being connected for simultaneous operation to feed an impression-sheet direct to said drum and roller and at substantially the same speed as that of said drum and roller, a friction-sheave connected with one of said rolls, a clutch between the 70 rolls and said sheave, and an adjustable sector carried by a moving part of the apparatus and having a curved periphery coöperating intermittently with said sheave, substantially as described. 80

2. The combination with a printing-drum and an underlying pressure-roller, of a sector pivoted upon and movable with said drum and having an elongated slot concentric with its pivot, and sector-securing means coöperating with said slot and said drum, feed-rolls mounted in fixed bearings and connected for simultaneous operation, and means intermediate of said feed-rolls and said sector, and coöperating with both, whereby the movement of said sector simultaneously with said drum will transmit corresponding, but intermittent, feeding movement to said feed-rolls, substantially as described. 90

3. The combination with two feed-rolls, 100 connected for simultaneous operation, one of said rolls having a plurality of separated roll-sections, and means for imparting movement to said rolls, of a plate having an opening therein through which the periphery of one of said rolls protrudes, and a guide located over said plate and at an angle thereto, said guide having fingers along one edge thereof terminating adjacent to the point of coaction of said rolls and in juxtaposition to said sections upon one of said rolls, substantially as set forth. 105

4. The combination with a printing-drum and a coöperating pressure-roller, of two feed-rolls in juxtaposition to the point of coaction of the drum and roller, gearing between said rolls, a friction-sheave, a connection between said sheave and one of said rolls whereby the sheave drives the rolls, a clutch in said connection, and an adjustable sector 110 carried by said drum and having a curved periphery coöperating intermittently with said sheave, substantially as described. 115

5. The combination with a printing-drum and a coöperating pressure-roller, of a sector pivoted upon and movable with the drum and having an elongated slot concentric with its pivot, sector-securing means coöperating with said slot and said drum, a pair of feed-rolls, gearing between said rolls, a friction- 120

125

sheave mounted in position to coöperate with said sector, a connection between said sheave and said rolls whereby the movement of the sector simultaneously with said drum transmits corresponding but intermittent feeding movement to the feed-rolls, and a clutch in said connection, substantially as described.

This specification signed and witnessed this 25th day of May, 1907.

ALBERT B. DICK.
